UNITED STATES PATENT OFFICE.

ARDELLO M. ROWE AND CLAUDE O. ROWE, OF BELLINGHAM, WASHINGTON.

AUTOMATIC MOVING-TARGET SHOOTING GALLERY.

Application filed September 20, 1927. Serial No. 220,649.

Our invention relates to improvements in automatic, moving-target shooting galleries, and has for an object to provide a shooting gallery in which toy balloons are caused to move continuously in a circuit a part of which is within range for target practice.

Another object of our improvement is to provide for adding other toy balloons to said circuit to replace those destroyed under fire.

10 And a further object of our improvement is to provide for the movement of said targets in erratic and not uniform paths when within range.

We attain these and other objects of our 15 invention with the structure and mechanism illustrated in the accompanying drawing, which forms a part of this specification, in which the front elevation of one form of our invention is shown in perspective.

20 Certain parts are broken away to show other parts hidden thereby.

More particularly: An open-front chamber 1 has pyramidal ceiling 2. In front of said chamber is counter 3 before which both the 25 attendant and the marksmen stand.

30 Tube 4 connects with a hole in the apex of ceiling 2 and leads across the top of said chamber, down one side thereof and then passes across the open front of the chamber near the floor to connect with the outer end of transverse trunk 5 at hole 6. The other end of trunk 5 connects with the inlet of casing 7 of exhaust fan a^7 driven by electric motor 8.

35 In the outer end of trunk 5 through its top wall is rectangular hole 9, and from the inner end of said hole grating 10 inclines downward and toward hole 6 to the bottom of the trunk to prevent any larger body from passing toward 40 exhaust fan a^7 through trunk 5.

Double valve 11, a^{11} is mounted for oscillation on shaft 12 through holes in the upper edges of the side walls of trunk 5 proximate to the inner end of hole 9 and has crank 13 on 45 its outer or front end and counterweight 14 on a crank on its rear end. Counterweight 14 is heavy enough to cause valve 11, a^{11} to assume a horizontal position when free to do so.

The rear end of line 15 is fastened in an eye 50 in the end of crank 13, passes through lead screw eye a^{15} fastened in the floor and thence to counter 3 over the top of which its front end lies within easy reach of the gallery attendant.

55 Tube 16 connects with hole 17 through the top of counter 3 preferably near line 17 and

passes downward beneath said counter and then rearward to connect with tube 4 near trunk end a^5 .

Hinged cover 18 is adapted to close hole 60 17 or stand vertically to uncover said hole as illustrated.

Outwardly flaring tube 19 is connected to a side wall of chamber 1 near the front edge thereof and quite near the floor in hole a^{19} . 65 In front of the outer end of tube 19 is a small ventilating fan 22 driven by electric motor 21 and mounted on bracket 23. This fan is operated to force air from without the chamber within and across the same. 70

Outwardly flaring tube 24 is connected to the other side wall of chamber 1 midway thereof in hole a^{24} . In front of the outer end of tube 24 is a small ventilating fan 26 operated by electric motor 25 and mounted on 75 bracket 27. This fan is operated to force air from without the chamber through hole a^{24} across said chamber.

Designating numbers 28—34 indicate several small toy balloons in different positions 80 of operation.

It is assumed that fans a^7 , 22 and 26 are in operation. Then, since valve a^{11} closes the outer end of trunk 5, exhauster a^7 tends to cause valve 11, a^{11} to revolve with shaft 12 85 to a horizontal position. This movement of said valve in a forward revolution is also aided by counterweight 14. It is assumed that the attendant holds line 15 to prevent the said turning of valves 11, a^{11} as stated retaining them in their illustrated positions. 90

Balloon 28 is within the trap in the outer end of trunk 5 and has been prevented from passing further in said trunk toward fan a^7 by grating 10. This balloon has been drawn 95 into said trap from tube 4 through hole 6 while valves 11, a^{11} were in a horizontal position with the former covering, or closing, hole 9.

With valves 11, a^{11} in a vertical position, as 100 illustrated, the exhaust fan can exert no pull on balloon 28 and its buoyancy will cause it to rise through hole 9 out of said trap to a position at 29. Then it will proceed upward till caught by transverse air currents from fan 105 22 when it will move diagonally upward toward the left to position 30. As it moves upward near the left side wall of the chamber 1 it will come within the influence of transverse air currents from fan 26 through hole a^{26} and 110 be driven in an upward and right-hand direction to position 31. Thence it will move up-

ward to position 32 and pass beneath ceiling 2 to position 33 in the apex thereof. In the above description the several balloons appearing in the illustration within the gallery chamber 1, 2 are referred to as several positions of the same balloon. This they may be but for the benefit of further description they also may be considered as several balloons simultaneously appearing in different positions in elevation and lateral disposition in chamber 1, 2; since, in practice, it is customary to have at least the number of balloons shown in the illustration appearing together for target purposes.

15 When several balloons, as 29, 30, 31 and 32, are within range for target purposes the attendant releases line 15 which permits valve a^{11} to open communication between fan a^7 and tubes 4 and 16. At the same time valve 11 closes hole 9 and air will be drawn into tube 4 from chamber 1, 2 and into tube 16 through opening 17, if cover 18 is open, as illustrated. Or, if cover 18 is in a horizontal position, closing opening 17, the full effect of exhaust fan 25 a^7 will be concentrated on tube 4 and the balloons appearing in chamber 1, 2 in the illustration will be successively drawn into tube 4 and delivered therethrough into the trap against grating 10 as shown at 28. From this 30 position they may be released by raising valve 11 and closing valve a^{11} ; which, as stated, is accomplished by pulling on line 15. In this manner balloons 28-33 are maintained in circulation through tube 4 and chamber 1, 2 35 providing targets for the purposes stated.

When a balloon target is destroyed under fire it is conveniently replaced with another balloon and the desired number of targets maintained within range by closing valve 11 and opening valve a^{11} with tension on line 15 and then feeding in balloon 34 through the uncovered opening 17, as illustrated. Assuming that exhaust fan a^7 is powerful enough to maintain operative suction on both of tubes 16 and 4, which it must be in practice, balloon 34 is drawn through tube 16 into tube 4 and thence into the trap against grating 10 as at 28. From the trap it is released under its own buoyancy by opening valve 11 and closing valve a^{11} , as explained, and then takes its place in the circulation of targets to replenish their number.

It thus appears that, with the apparatus and appurtenances illustrated and described, the buoyant targets may be caused to pass within range over devious paths and their losses replenished as the use of the shooting gallery proceeds and all of the operations continuing automatically except for the assistance and control which may easily be given by one attendant while at the same time attending to the usual duties involved in operating a shooting gallery.

The simple means described are sufficient for the objects of this improvement but their

equivalents are also within the purview of our invention.

In practice, most of the apparatus disclosed in the drawing is covered by screens sufficiently resistant to stray bullets to protect the mechanism from injury thereby, small screen 35 shown in front of the trap only is extended to shield tube 4, trunk 5, and fans 7, 21 and 25 as well.

Having thus disclosed our invention, what we claim as new therein and desire to secure by Letters Patent is,—

1. In a shooting gallery the combination of an open-front chamber and means to cause a circulation of buoyant targets from below in said chamber upward through the same and then downward to the said lower part of said chamber to again pass upward therein. 80

2. In a shooting gallery the combination of an open-front chamber, and means to cause a circulation of buoyant targets from below in said chamber upward therethrough in varying and irregular paths and then downward to the said lower part of said chamber to again pass upward therein. 90

3. In a shooting gallery the combination of an open-front chamber, means to cause a circulation of buoyant targets from below in said chamber upward therethrough and then downward to the said lower part of said chamber to again pass upward therein, and means to introduce other buoyant targets into said circulation from a point away from said chamber during the progress of said circulation. 95

4. A shooting gallery consisting of an open-front chamber having a peaked ceiling, a tube leading from the vertex of said ceiling to an exhauster below said tube having an escape port in its top near said exhauster, a grating across said tube near said escape port therein and between the same and said exhauster, valves adapted to simultaneously open said escape port and close said tube between said grating and said exhauster and vice versa, and means to operate said valves at a distance from said chamber. 105

5. A shooting gallery consisting of an open-front chamber having a peaked ceiling, a tube leading from the vertex of said ceiling to an exhauster below said tube having an escape port in the top thereof near said exhauster, a grating across said tube near said escape port therein and between the same and said exhauster, valves adapted to simultaneously open said escape port and close said tube between said grating and said exhauster and vice versa, means to operate said valves at a distance from said chamber, and ventilating fans on opposite sides of said chamber in staggered relation adapted to cause transverse air current in said chamber in opposite directions at different levels. 120

6. A shooting gallery consisting of an open-front chamber having a peaked ceiling, 130

a tube leading from the apex of said ceiling to an exhauster below said tube having an escape port in the top thereof near said exhauster, a grating across said tube near said escape port therein and between the same and said exhauster, valves adapted to simultaneously open said escape port and close said tube between said grating and said exhauster and vice versa, means to operate said valves

at a distance from said chamber, a branch tube leading from a point near the floor in front of said chamber at a distance therefrom connected with said main tube between said escape port therein and the said ceiling of said chamber, and means to close the entrance of said branch tube.
